Attorney.

UNITED STATES PATENT OFFICE.

WILLIAM R. GORRELL, OF CARSINS RUN, MARYLAND, ASSIGNOR OF ONE-HALF TO RICHARD H. WEBSTER, OF ABERDEEN, MARYLAND.

HAT-PIN.

SPECIFICATION forming part of Letters Patent No. 599,526, dated February 22, 1898.

Application filed April 12, 1897. Serial No. 631,713. (No model.)

To all whom it may concern:

Be it known that I, WILLIAM R. GORRELL, a citizen of the United States, residing at Carsins Run, in the county of Harford and State 5 of Maryland, have invented certain new and useful Improvements in Hat or Shawl Pins; and I do declare the following to be a full, clear, and exact description of the invention, such as will enable others skilled in the art 10 to which it appertains to make and use the same.

My invention has relation to a hat or shawl pin; and the object is to provide a device of this character by means of which the pin after it has been attached will not accidentally 15 become disengaged.

With this object in view the invention consists of certain features of construction and combination of parts, which will be hereinafter fully set forth and claimed.

In the accompanying drawings, Figure 1 is a plan view of my improved pin, and Fig. 2 is a similar view of another form of my invention.

25 In Fig. 1, 1 denotes the shank of the pin, which is of usual construction. At the rear end the shank is bent outwardly, as shown at 2, thence upwardly, as shown at 3, thence inclined inwardly and downwardly, as shown 30 at 4, thence coiled to form a spring 5. Thence it is bent upwardly, as shown at 6, thence downwardly, as shown at 7, inwardly, as shown at 8, thence downwardly, as shown at 9, and thence inwardly and formed with a 35 point, as shown at 10. This construction provides two spring-arms *a* *b*, the energy of the spring being exerted to force the safety-point into the material when the body of the pin is inserted therethrough and thus prevent its 40 accidental withdrawal.

In attaching the pin its spring-arms *a* and *b* are grasped between the finger and thumb and compressed to raise the safety-hook away from the shank of the pin. The pin is then 45 inserted into the goods and by releasing the pressure of the spring-arms *a* and *b* the spring

will force the hook into the goods and prevent the removal of the pin until the said arms are compressed together.

In the construction shown in Fig. 2 I have 50 formed the shank of the pin with an eye *c*, adapted to receive the safety-hook. This construction will more effectually prevent the accidental disengagement of the safety-hook with the material through which the pin has 55 been passed.

Although I have specifically described the construction and relative arrangement of the several elements of my invention, I do not desire to be confined to the same, as such 60 changes or modifications may be made as clearly fall within the scope of my invention without departing from the spirit thereof.

Having thus described my invention, what I claim, and desire to secure by Letters Pat- 65 ent, is—

1. The herein-described pin provided with the diverging spring-arms *a*, *b*, the pin-shank 1, connected to one of said arms and the safety-point 10 connected to the other arm, 70 said point 10, normally lying across the plane of the shank 1 to hold the pin into the material, the arms *a*, *b*, serving to withdraw the point 10, when pressed together, substantially as described.

2. The herein-described pin provided with the diverging spring-arms *a* *b*, the pin-shank 1 having the eye *c*, said shank connected to one of said arms, and the safety-point 10 connected to the other arm, said point 10 nor- 80 mally projecting through the eye *c* and lying across the plane of the shank 1 to hold the pin into the material, the arms *a* *b* when pressed together serving to withdraw the point 10, sub- 85 stantially as described.

In testimony whereof I hereunto affix my signature in presence of two witnesses.

WM. R. GORRELL.
